FLASH LIGHT

Application filed March 16, 1927. Serial No. 175,763.

This invention relates to flash lights of the type which is easily portable and adapted to be carried in the hand, and has for an object to provide a flash light structure, and particularly a switch control, which will be more simple in construction and may be manufactured and assembled at less cost than the structures now generally used.

It is also an object of the invention to provide an improved switch construction for this type of devices in which the liability of short circuiting the battery is reduced to a minimum, and in which the weight of the battery is prevented from injuring the lamp bulb. 10
15 It is a further object of the invention to provide a switch in which there is a wiping effect between the switch and the stationary contacts to keep the contacting surfaces clean and always insure a good electrical contact. 20
25 It is a still further object to provide a switch in which the liability of accidental shifting thereof to the "on" position is reduced to a minimum, and therefore, the liability of accidental closing of the switch and exhausting the battery when the light is placed on a flat support or carried in an automobile kit is greatly reduced.

With the foregoing and other objects in view, I have devised the construction illustrated in the accompanying drawing forming a part of this specification. In this drawing—

Fig. 1 is a side elevation of a flash light involving my improved construction with portions of the casing broken away to more clearly show the construction. 30
35

Fig. 2 is a transverse section substantially on line 2—2 of Fig. 1 and showing the switch in the "off" position.

Fig. 3 is a detail section through the casing showing the switch in the "on" position.

Fig. 4 is a similar view looking from the left of Fig. 3.

Fig. 5 is a partial side elevation and a partial section through a portion of the casing showing the use of a different type of joint.

Fig. 6 is a top plan view of the switch contact and its support.

Fig. 7 is a side elevation thereof.

Fig. 8 is a transverse section through the switch element and its support substantially on line 8—8 of Fig. 6.

Fig. 9 is a front elevation and top plan view of a closing member for the slot in the casing. 55

Fig. 10 is a section similar to Fig. 2 showing a slightly different construction; and

Fig. 11 is a vertical section through the casing showing the construction of Fig. 10 in elevation. 60

The flash light comprising a casing preferably comprising two sections including a body section 10 and a shorter end section 11 which is secured to the body section by a suitable joint. In the form shown in Figs. 1 to 4 this joint is a bayonet joint comprising L-shaped or bayonet slots 12 leading from the lower end of the end section 11 on opposite sides thereof and adapted to receive the body of a pair of rivets 13 carried by the body section. It is preferred that the inner end of the bayonet slots be provided with a recess 14 to cooperate with a spring, later to be described, to form a lock to prevent accidental separation of the two sections of the casing. 65
70
75

In Fig. 5 instead of using the bayonet connection I have shown the use of a screw connection in which the upper end of the body section of the casing and the lower end of the end section are correspondingly threaded as indicated at 15 and 16 respectively. 80

At the closed end of the body section 10 is mounted a spring 17. This spring is preferably of a piece of round wire of the desired stiffness and includes a base portion 18 seated in the groove formed by a bead 19 in the end of the casing to thus hold the spring in position, and at its upper end it presses against the lower end of the battery 20. This battery is of the standard type, which usually comprises a zinc shell enclosed in a fibre covering, such as stiff paper, so that the side walls are insulated by this covering, but the end of the metal casing is exposed so that it will engage the spring 17 and will be grounded thereby on the casing 10. The other terminal of the battery is usually in the 90
95
100

center thereof and is exposed at the opposite end as indicated at 21.

Mounted in the free end of the end section 11 of the casing is a reflector 22 of any suitable shape. In the present form it is shown as substantially conical and is threaded at its inner end or apex, as shown at 23, to form a lamp socket. The lamp is of the standard type used in this class of devices including 10 a screw shell 24 adapted to be threaded into the socket 23 and form electrical contact therewith. It also has the usual central contact 25 insulated from the screw shell 24, and the shell and central contact are electrically 15 connected in the usual manner to the opposite ends of the filament, not shown, which is enclosed in the usual glass bulb 26. The open end of the reflector is closed by the usual glass lens 27 clamped to the open side of the reflector. The reflector has a flange 28 resting 20 against the end of the section 11 of the casing with the flat side of the lens resting against this flange, and they are both clamped to the casing by the ring 29 threaded on the casing, 25 as shown at 30, with the flange 31 of the ring engaging the face of the lens.

My improved control switch comprises a supporting member 33 of suitable insulating material, such as a pressed fibre or molded 30 phenolic condensation product, and it is shown in the present structure as a plate of substantially oval shape. At one end this plate is provided with a lug or extension 34 extending through an opening 35 in the side 35 of the casing, and on the opposite side of the casing is a slot 36 through which a lug 37 projects, this lug being on the opposite end of the support. It will, therefore, be noted that the lug 34 cooperating with the sides of the 40 opening in the casing provide a pivot for the support 33 and the lug 37 projects sufficiently from the surface of the casing to be engaged by the thumb or finger of the operator and thus provide an operating means to swing the 45 support on its pivot. It is also to be noted that this support extends transversely of the casing and is mounted between the battery and the lamp socket.

Mounted on the support by any suitable 50 means is a switch member 38. A convenient and simple way of mounting this member is to provide the support with a slot or opening 39, and the switch member preferably comprises a flat strip of resilient metal passing 55 through this opening and extending substantially parallel with this support on the under and upper sides thereof, as shown at 40 and 41, respectively. The switch may have lugs 42 on opposite sides of the portion 41 bent 60 over the edge of the slot to hold the switch member in proper position.

It is preferred that when the elements are assembled the lower portion 40 of the switch member should at all times engage the end 65 of the battery terminal 21 although this is

not absolutely essential. Under these conditions, however, the resilient action of the switch forms a spring support for the battery, and should the light be dropped would, therefore, because of its cushioning effect, tend to prevent injury to the battery or the other elements. The battery terminal will be held against this switch contact by the spring 17 at the lower end of the battery to insure proper electrical contact between the switch and the battery terminal. The other portion 41 of the switch element is also spaced somewhat from the surface of the support 33 and forms a spring contact to engage the central contact 25 of the lamp. The free end of the portion of the switch element is bent downwardly somewhat to form a rounded end 43 so that it will slide easily into engagement with the lamp contact, and the top surface of the support may, if desired, be provided with a recess 44 to permit the desired movement of this contact.

The upper portion 41 of the switch element is of such a length that when the support 33 is in the position shown in Figs. 1 and 2 this portion of the switch is out of engagement with the central lamp contact 25, and therefore, the circuit through the lamp is open, although the lower portion 40 of the switch is still in engagement with the terminal 21 of the battery. If now the support is swung to the right, as viewed in Figs. 1 and 2, by swinging the lug 37 to the right in the slot 36, this movement will bring the upper portion 41 of the switch into engagement with the central lamp contact 25, as shown in Fig. 3, and will, therefore, close the circuit through the lamp because the screw shell contact of the lamp and the opposite end of the battery are both grounded on the casing. It will be noted that movement of the switch element is a wiping movement across both the terminal of the battery and the lamp contact and will, therefore, tend to always keep these contacts clean and make a good electrical connection.

The left hand end of the slot 36 is provided with a recess in the upper edge thereof to provide a shoulder 45 and serve as a stop to prevent accidental shifting of the switch support to the "on" position. It will be noted that when the elements are assembled the spring 17 at the lower end of the battery is compressed and forces the battery upwardly and holds its terminal 21 against the switch member, always insuring proper contact therewith, and it also presses the lug 37 against the upper edge of the slot 36. Therefore, when the switch support is in the left hand position of Figs. 1 and 2 and the switch is in the "off" position the lug 37 is held in the recess in the upper edge of the slot by this spring and the support is, therefore, held by the shoulder 45 against movement to the "on" position. In throwing the switch to

the "on" position the lug 37 is first moved downwardly in the slot to free it from the shoulder 45, and it may then be forced to the right to move the switch to the "on" position. This feature prevents accidental movement of the switch to the "on" position, and thus prevents accidental exhausting of the battery when the light is laid on a flat support or is carried in an automobile or the like.

It is also to be noted that as the switch support 33 is located between the battery and the lamp socket this support forms a support for this end of the battery to prevent movement thereof longitudinally of the casing, and therefore, should the lamp be dropped with the top or lamp end down the weight of the battery will be taken by this support and it will not be transmitted to the lamp, and therefore, the lamp will be protected against injury. The spring effect of the switch element also gives a cushioning effect which will tend to prevent injury to the battery. As the switch support 33 is usually made of some fibrous or other non-metallic material a metal rivet 46 may be mounted in the lug 37 in position to engage the top edge of the slot 36 to take the wear of the edge of this slot against the side of the lug as the switch is moved to and from the "on" position.

In assembling the lug 37 is inserted in the slot 36 and then the lug 34 may be inserted in the opening 35. As the casing is usually made of thin sheet metal it will have sufficient flexibility to permit this. As the spring 17 tends to force the battery and the end section 11 upwardly it will hold the rivets 13 in the recesses 14 in the bayonet slots 12 and thus prevent accidental separation of the sections of the casing. It is also desirable to close the slot 36 to prevent entrance of dirt. For this purpose I provide a curved metal plate 47 having an opening 48 to receive the lug 37. This plate will lie next to the inner surface of the casing and close the slot 36. It will move laterally with the lug 37 and is of sufficient length to always cover the slot.

In Figs. 10 and 11 I have shown a somewhat different construction of switch. Here instead of having the switch contact 38 mounted on an insulating switch support pivoted at one side, it is mounted on an insulating support 49 having extensions 50 and 51 at its opposite ends extending through openings in the opposite sides of the casing 11, and guided for transverse sliding movement therein. These extensions may be round or other desirable shapes but are preferably rectangular in rectangular openings in the casing to help prevent the support from turning. The switch contact 38 is mounted on this support in the same manner as on the support 33. The circuit is closed or opened by pushing inwardly on the ends of the ex-

tensions 50 and 51 to slide the support 49 and bring the spring contact 41 into or move it from engagement with the lamp contact 25. Portion 40 remains in engagement with the battery terminal 21 the same as in the first form. The extension 51 may have a notch 52 in its top side to receive the edge of the casing 11 and thus prevent accidental closing of the switch by pressure on the end of the extension 51 when laying it on a flat support or placing it in a tool box. The spring 17 at the lower end of the battery together with the spring action of the contact 40 will tend to hold the edge of the opening against the bottom of this notch, as shown in Fig. 11. To operate it the extension 51 is first pressed downwardly to remove the notch from the edge of the opening and then the support 49 may be shifted to close the circuit.

Having thus set forth the nature of my invention, what I claim is:

1. In a flash light, a casing adapted to hold a battery and provided with an opening in the wall thereof and a slot in the opposite wall, a lamp socket at one end of the casing, an insulating support having an extension in said opening whereby it is pivotally mounted and also provided with an operating extension projecting through said slot, and a switch member carried by said support and adapted to bridge a terminal of the battery and a contact of a lamp in said socket.

2. In a flash light, a casing adapted to hold a battery, a lamp socket mounted at one end of the casing, said casing having an opening and a slot respectively on opposite sides thereof, an insulating plate mounted between the battery and said socket, said plate having an extension in said opening forming a pivotal support and an operating extension projecting through said slot, and a switch member comprising a resilient plate extending through an opening in said insulating plate and including contacts on opposite sides thereof to bridge a lamp contact and a terminal of the battery.

3. In a flash light, a casing adapted to hold a battery and provided respectively in opposite side walls with an opening and a slot, a transversely extending insulating support having an extension in said opening to form a pivot and another extension projected through the slot to provide an operating means, a switch contact carried by said support and adapted to engage one terminal of the battery, said support cooperating with the walls of the casing to form a support for the battery, a lamp socket on the opposite side of the support from the battery, and a lamp in said socket, said switch contact having an extension adapted to engage a contact of said lamp.

4. In a flash light, a casing adapted to hold a battery, a lamp socket at one end thereof, a lamp in said socket, an insulating sup-

port mounted to move transversely of the casing between the battery and said socket, and an integral one-piece resilient switch contact extending through an opening in the support and having spring portions on opposite sides thereof each tending to move away from the support and adapted to engage a battery terminal and a lamp contact respectively, said contact having integral means ~~en-~~ ¹⁵ gaging the surface of the support to hold the spring portions in these positions.

5. In a flash light, a casing adapted to hold a battery, a lamp socket mounted at one end of the casing, said casing having an opening and a slot respectively on opposite sides thereof, an insulating plate mounted between the battery and said socket, said plate having an extension in said opening forming a pivotal support and an operating extension projecting through said slot, a switch member mounted on said plate adapted to bridge a terminal of the battery and a lamp contact including a spring contact on one side of the plate, and said slot having a shoulder cooperating with said operating extension and said spring contact to retain the plate in one position.

In testimony whereof I affix my signature.
GILES C. FULLMER.
